UNITED STATES PATENT OFFICE.

WILLIAM BAXTER, JERSEY CITY, NEW JERSEY, ASSIGNOR, BY MESNE ASSIGNMENTS, TO THE HYDRODYNAMIC TRANSMITTER COMPANY, OF NEW YORK, N. Y.

APPARATUS FOR DRAINING MINES.

SPECIFICATION forming part of Letters Patent No. 269,167, dated December 19, 1882.

Application filed January 12, 1882. (No model.)

To all whom it may concern:

Be it known that I, WILLIAM BAXTER, a citizen of the United States, residing in the city of Jersey City, in the county of Hudson and State of New Jersey, have invented certain new and useful Improvements in Apparatus for Draining Mines, fully described and represented in the following specification and the accompanying drawings, forming a part of 5 the same.

My invention consists in the improved apparatus or combinations of mechanism herein set forth for draining mines, the same being applicable in many cases where water is to be raised from springs, wells, quarries, or locations other than mines where it may be difficult to transmit steam thereto.

My invention is an improvement upon the methods heretofore devised to use a balanced 20 column of water for operating a motor, and furnishes a means of avoiding synchronous movements in different parts of the apparatus by passing the moving fluid entirely through the motor and returning it to the top of the 25 operating-column, where it is received in a tank, and drawn thence to be used over again. The use of such a receiving-tank avoids the employment of pass-over valves and priming devices, which have been required in other constructions.

My invention also includes a special form of 30 combined motor and pump, which consists in a three-cylinder rotary device so constructed as to have the pressures upon its axis entirely balanced. This device I term a "transmitter," and, as its affords the most efficient means of carrying out my method, my invention will first be described in connection therewith.

To illustrate the action of the apparatus 40 herein described, I will suppose a rotary motor and pump placed in the bottom of a mine and a rotary pump and tank located outside the mine. The rotary pump would be arranged to draw water from the tank and would be 45 propelled by any kind of power. The inlet and outlet of the rotary motor in the mine would be provided each with a pipe leading to the level of the pump outside, and when filled with water it is obvious that the pressures in such 50 pipes would be balanced, and that if one were

connected with the discharge from the upper pump the rotary motor would be propelled and the water used would be discharged from the other pipe, by which it could be led to the receiving-tank near the upper pump. Such an operation could be continued as long as power was applied to the upper pump, and any loss of water from leakage could be made up by filling the tank from any source. The motor in the mine would of course exert the power 60 applied to the upper pump, less the friction in the mechanism, and such power would be available for operating any drainage-pump connected therewith. The water from such drainage could be also led to the receiving-tank, 65 and an overflow provided to dispose of it thereafter. As a rotary motor can be constructed without any "dead-points," it would be ready to start whenever movement and pressure were produced in the inlet-fluid, and, as the flow of 70 such fluid would be uninterrupted by the structure of the rotary device, it could be led from one rotary motor to another, and propel any number thereof serially, provided the original pressure-pump exerted sufficient force to overcome their combined resistances. By such a method and construction I am enabled to secure many advantages not attainable by the use of steam boilers and engines located in the 75 mines or located upon the surface of the mine 80 and operating pumps by mechanism extended down the shafts. It also secures a greater economy than the use of steam-pumps in the mine supplied with steam conducted from outside the mine in pipes, for the reason that 85 it affords an opportunity to use the most improved and economical engines, boilers, and pumps, at a cost far below that of the Cornish engines, while operating with equal efficiency.

My apparatus also operates more economically, both in its wear upon the plant employed and in the cost of operation, than the reciprocating devices heretofore used, because the flow of water propelled by rotary devices is practically continuous, and thus avoids all the 90 jars and concussions occasioned in the water-pipes by intermittent movements. Such a flow also secures a saving in the power employed, as the momentum or inertia of water strongly resists any changes in its velocity. The suc- 95 100

tion-pipe also lifts the water more favorably from the cistern or basin in the mine, as there is no sudden or intermittent suction excited to disturb the water and its sediment. Although I have referred to a rotary pump as the primary mover of the water-column, it is evident that any means may be employed which will operate most economically, and I do not therefore limit myself to the use of a rotary prime mover. As compound engines are now used with great efficiency to produce a constant flow of water by means of duplex pumps, I have shown the same herein, as being the most economical for the prime mover, while I consider the rotary motor and rotary drainage-pump the most effective for use down in the mine for the reasons stated above.

In the drawings annexed, Figure 1 is a side elevation of the works located above the ground near a mine-shaft, with a section of the latter, containing my combined motor and pump, with its connections. Fig. 2 is a section through the motor and pump on line $x-x$ in Fig. 1, and Fig. 3 is a central section of the same on line $y-y$ in Fig. 2.

A is the primary force-pump, which I shall call a "pressure-generator" or "generator" herein.

B is the motor; C, its inlet-pipe; D, its outlet-pipe; E, a receptacle or tank receiving the water therefrom, and F an overflow-pipe discharging to any lower level.

The generator is represented with pump-cylinder a and compound steam-cylinders b c , the pipe C leading from the pump-delivery d to the inlet of the motor at e , and the pipe D leading from the outlet of the motor at f to the top of the tank E.

G is the suction-pipe of the generator, and is connected to the bottom of the tank.

The boilers for operating the steam-engine cylinders b c are not shown, as they may be of any desired character.

In Fig. 2 is shown one form of rotary engine or pump to illustrate the mode in which I combine a pump and motor so as to balance the pressures upon the axis and reduce the friction to the lowest point. The rotary pistons are shown as formed with uniform cogs at equal intervals, and are equivalent to the Holley rotary engines and pumps, of slightly different construction, whose mode of operation is well known. Two such pistons, b' , are arranged in the casing upon axles m , and the casing is formed with partitions n n , (see Fig. 2,) transverse to the axles, at such distances from the heads h as to form three chambers, i , i , and j , the latter being twice as large as the former and located in the center between them. A pipe, e , enters the central chamber and leads to it the water under pressure from the pipe C, thus causing the pistons therein to rotate as a motor with a force due to the pressure produced in the generator. The partitions n n are formed with holes around the axles of such size that the pistons in the chambers i i may be formed integral with the central pistons or

united thereto by collars o , so that the rotation of the motor will be imparted to the outer pistons to operate them as pumps. Pipes l l are connected to the outer chambers, i , and united in a single suction-tube, H. Discharge-pipes p p are also connected with the chambers upon the opposite side, and are shown joined to the delivery-pipe f , so that the pistons in the chambers i i may operate to draw any water supplied to the pipe H and force it into the outlet-pipe of the motor, whence it is conveyed to the tank or otherwise carried from the mine.

In cases where the suction-pipe H draws its water from a clean spring or well, the construction shown for the three pipes p and f is quite suitable; but if the water raised by pipe H is unfit to enter the pressure-generator cylinder a , the pipes p would require to be united and conducted away from the tank E, so that the water therein might be adapted for constant use in operating the motor without injury to its working parts.

The form of the pistons b' may be modified as desired; but some form analogous to that shown avoids the use of external gearing to keep the pistons in proper relative positions, and the necessity for stuffing-boxes on the axles when such gearing is used. As shown in Fig. 2, the shell of the casing is cast in halves with the partitions in it, and joined by flanges q at the center line, being bored out by suitable tools to fit the pistons. The application of heads m' at the ends then makes the casing complete, and without any moving parts upon its exterior to suffer derangement.

If desired, the axle m can be projected through one of the heads, as shown at k , and formed with a square end for turning the pistons around when obstructed, the end being protected by a cap, g , secured over the end k by a screw-thread, g' . With the motor-piston arranged between two pumping-pistons, as shown, it will be found that the precise upward pressure exerted upon the axle m by the generator is balanced by the downward pressure upon the pumping-pistons exerted by the weight of water discharged from pipes p . The pressure of the water in pipes e and f being exerted upon opposite sides of the motor-piston—one above and the other below—no thrust is produced upon the axle, and all tendency in the pistons to wear out of center is entirely prevented.

From the above statement it is plain that various means may be devised to operate according to my described method, which consists essentially in forcing a balanced column of water by means of a generator through a rotary motor back to a tank at the level of the generator.

By my mode of operation the transmitter B can be located in the mine at any convenient point and readily connected by the required pipes; and a number of such transmitters may be situated at different points upon the same vein and actuated by connection to the same generator, thus concentrating the expense and

labor of attendance at one spot outside the mine, and locating the working machinery in the most favorable situation for access.

As the connection of several motors, in the manner described, is rendered possible by the substitution of rotary motors for the reciprocating ones heretofore employed, and the use of a tank to compensate for leakage and other variations in place of the synchronous movements attempted heretofore, it will be seen that my improved method consists in operating such pumps in connection with a tank, that the latter may serve to compensate for the lack of the other features heretofore combined with reciprocating pumps to fit them for operating automatically with water-pressure.

I am aware that a rotating motor has been arranged, as in Patent No. 220,108, dated September 30, 1879, to carry without any external bearings a rotary fan or pump at each side of it, and I do not therefore claim the combination of a motor and two pumps, broadly; but as my transmitter has a bearing in the head *h*, outside of the pumping-pistons, it is evidently a different construction from that patented above; and the difference is further noticeable in the fact that the casing is expressly intended to include all the operative parts, and to cover and protect them in situations where they are much exposed to water, dirt, and accident, and which the said patented device

would not be so well adapted to resist with a construction so different from mine. In case the water pumped up by the transmitter is not suitable to use in the generator, it would not be thrown into the tank at all, but delivered elsewhere, and the loss by leakage and other causes in the balanced column would be made up by supplying the tank with clean water from independent sources from time to time, as required.

Having thus described my invention, I claim the same, as follows:

1. In combination with the force-pump *A*, motor *B*, and inlet and delivery pipes *C D*, operating as described, a tank or receptacle, *E*, provided with overflow *F* and connection to the inlet of the force-pump, substantially as and for the purpose set forth.

2. The transmitter herein described, consisting of three rotary pistons in one cylinder, arranged and operated so as to balance the pressures upon the axis, substantially as shown and described.

In testimony whereof I have hereunto set my hand in the presence of two subscribing witnesses.

WM. BAXTER.
